PEDESTAL SUPPORT FOR A BALANCE OR SIMILAR ARTICLE

Thomas S. Watson, Whittier, Calif., assignor to Watson Bros., Los Angeles, Calif., a partnership composed of James W. Watson and Thomas S. Watson

Filed Oct. 18, 1967, Ser. No. 9,059

Term of patent 14 years

(Cl. D52—10)

FIG. 1

FIG. 3

FIG. 1 is a front perspective view of a pedestal support for a balance or similar article showing my design;

FIG. 2 is a side elevational view of the article; and

FIG. 3 is a front elevational view thereof.

The side not showing in a mirror image of the side shown while the back is conventional.

I claim:

The ornamental design for a pedestal support for a balance or similar article, as shown and described.
